CLAIM

The ornamental design for a pair of hand warmers, as shown and described.

DESCRIPTION

FIG. 1 is a first perspective view of a pair of hand warmers showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front perspective view of one hand warmer, of a pair of two, shown separately, showing my new design;

FIG. 10 is a back perspective view thereof;

FIG. 11 is a front view thereof;

FIG. 12 is a back view thereof;

FIG. 13 is a left side view thereof;

FIG. 14 is a right side view thereof;

FIG. 15 is a top view thereof; and,

FIG. 16 is a bottom view thereof.

The claim is directed to the collective appearance of the pair of hand warmers shown in the figures. The hand warmers are arranged on the drawing sheet for the convenience of illustration, and the relative positioning of the hand warmers forms no part of the claimed design.

The broken lines shown in the drawings depict portions of the pair of hand warmers that form no part of the claimed design.
